Patented May 23, 1922.

Inventor

ERNEST L. ROSENBURGH

By his Attorney

E. M. Bentley

UNITED STATES PATENT OFFICE.

ERNEST L. ROSENBURGH, OF ROME, NEW YORK, ASSIGNOR TO ROME METALLIC
BEDSTEAD COMPANY, OF ROME, NEW YORK, A CORPORATION OF NEW YORK.

DESIGN FOR A BEDSTEAD END FRAME.

61,001.

Specification for Design.

Patented May 23, 1922.

Application filed July 14, 1921. Serial No. 484,771. Term of patent 7 years.

To all whom it may concern:

Be it known that I, ERNEST L. ROSENBURGH, a citizen of the United States, residing at Rome, county of Oneida, State of New York, have invented a new, original, and ornamental Design for a Bedstead End Frame, of which the following is a specification.

In the accompanying drawing, the figure

is a perspective view, illustrating a bedstead end-frame embodying the invention.

I claim:

The ornamental design for a bedstead end-frame as shown.

In testimony whereof, I have hereunto set my hand at Rome, Oneida County, New York, this 9th day of July, 1921.

ERNEST L. ROSENBURGH.
